RECORDING SYSTEM

James M. Brady, West Long Branch, N. J., assignor to the United States of America as represented by the Secretary of the Army

Application May 1, 1951, Serial No. 224,017

4 Claims. (Cl. 346—46)

(Granted under the act of March 3, 1883, as amended April 30, 1928; 370 O. G. 757)

1

The invention described herein may be manufactured and used by or for the Government for governmental purposes, without the payment of any royalty thereon.

This invention relates to recording systems and more particularly to recording systems using inked thread or wire as the recording elements.

The object of this invention is to provide a simplified recording unit for recording a plurality of variables on the same time axis in the form of minute points on a record receiving surface wherein all variables can utilize the same range on the receiving surface at the same time.

Known recording units (such as that described in copending application Ser. No. 199,120) utilize the fundamental conception of data actuated filaments moving in different planes parallel to a recording surface in combination with a tapper bar which periodically strikes the filaments causing them to contact a record receiving surface. However, such known recording units employ a complex filament carrying mechanism which moves the entire filament in response to data changes. A further object of this invention is to overcome the above and related disadvantages. Simplification of the filament carrying mechanisms is accomplished by a new and novel method of causing data actuated movement of record producing filaments over the record receiving surface. The method employed in this invention accomplishes data actuated movement of only one end of the record producing filament while the other end of the record producing filament is held fixed in contradistinction to the complete filament movement characteristic of known systems.

A further object of this invention is to provide a more compact recorder which minimizes the unit volume required per variable recorded. The use of this invention decreases the necessary physical size of the filament carrying carriages thus accomplishing this object.

Other objects of this invention will appear in the following description and appended claims, reference being had to the accompanying drawings wherein like reference characters indicate corresponding parts in the several views, and wherein Fig. 1 is a side view illustrating a form of mechanism whereby the invention may be carried out; Fig. 2 is a top view, partially broken away, which is taken through the points A, B, of Fig. 1; Fig. 3 is an amplified view of a filament carriage broken away through its center.

Referring to Figs. 1 and 2, the instrument is shown enclosed within a supporting frame 10

2 (broken away) on which the operating mechanism is mounted. Frame 10 contains bearings in which the rotary shafts 12, 14, 15, 16 and 17 are journaled. Fixed shafts 11, 13, 18 and 19 are rigidly secured to the frame. Motors 20, 21, 22, 23 and 24 transmit power to said rotary shafts through gear trains 25, 26, 27, 28 and 29, respectively. Rotary shafts 14 and 16 are threaded throughout their axial length and are in continuous engagement with the threaded bore of carriages 30 and 31, respectively. As shafts 14 and 16 are rotated by motors 21 and 22, said threaded engagement causes carriages 30 and 31 to move along shafts 14 and 16, respectively, in a direction determined by the shaft rotation. Carriages 30 and 31 are provided with bobbin type filament carrying devices 32 and 33 which are free to rotate about the shafts 16 and 14, respectively, and are preferably physically connected to said carriages by spring friction clips 34 and 35 which retard the angular motion of said carrying devices, in addition to holding them in fixed position relative to the carriages 31 and 30. Impregnated filaments 36 and 37 are suspended from the carrying devices 32 and 33 through positioning orifices 38 and 39 in flanges 40 and 41, which fix the position of one end of the operative portion of each filament 36 and 37 relative to each carriage 31 and 30, respectively, so that a change of position of carriages 31 and 30 along shafts 16 and 14 will cause a proportional change in position of filaments 36 and 37 along the recording surface of cylinder 42. The filaments 36 and 37 are passed through small positioning orifices in wall 43, which fix the position of the other end of the operative portions of filaments 36 and 37 relative to the recording surface 42, thence they are passed through spring members 44 and 45 which apply tension to said filaments and furnish elasticity to the filament system and finally the filaments 36 and 37 are connected to take up storage devices 46 and 47 which are rigidly connected to rotating shaft 12. A tapper bar 48 of conventional design is connected to arms 49 which pivot about shaft 18. Springs 50 are connected on one end of the supporting shaft 19 and on the other end to arms 49. Eccentric cams 51 are rigidly mounted on rotatable shaft 17, said cams being in engagement with arms 49 at the ends of said arms not attached to tapper bar 48. Tapper bar 48 is provided with a knife edge 52, so that as said knife edge is pressed against filaments 36 and 37 an impression is made against a record receiving

means 42 which is a cylinder moved at constant speed by motor 20 and gear train 25.

In the operation of the recording device, input data is fed to data responsive motors 21 and 22 which transmit power through gear trains 26 and 27 to shafts 16 and 14, respectively. Shafts 16 and 14 turn clockwise or counterclockwise in response to the transmitted power impulses causing lateral movement of carriages 31 and 30, because of their threaded engagement therewith causing the filaments 36 and 37 to assume different lateral positions relative to the recording means 42. Coincident with this lateral positioning of filaments 36 and 37, motor 24, through gear train 28, causes shaft 12 and, consequently, storage devices 43 and 47, to rotate, which causes filaments 36 and 37 to be taken up on said storage devices. The purpose in having the filament so taken up is to prevent its wearing out as the tapper bar 48 taps against the filaments.

A motor 23 operates through gear train 29 to rotate shaft 17, thereby driving cam 51 in a counter-clockwise direction. Intermittent action of the tapper bar 48 is effected in the following manner. In the position shown in Figs. 1 and 2, the tapper bar is engaged with the curved outer portion of cam 51, and as shaft 17 rotates, arm 49 actuated by spring 50 pivots about shaft 18 causing the tapper bar to press against filaments 36 and 37, located between it and the recording cylinder 42, and carry them into contact with the said recording cylinder. Once in each revolution of cams 51 the tapper bar presses the filaments against the recording cylinder; and, because the springs 50 urge arm 49 into engagement with cams 51, during rotation of cams 51, the arms 49 raise and lower tapper bar 48 while pivoting about shaft 18. The end result is that the tapper bar 48 uniformly and intermittently presses the filaments against the recording cylinder. When the tapper bar 48 is pressed against the recording cylinder 42 it has carried forward to the recording cylinder 42 both filaments 36 and 37, thereby making marks on the recording cylinder which are the area of the intersection of the filament and the knife edge 52 of the tapper bar in size. The recording cylinder 42 is rotated at a uniform rate and as the tapper bar 48 taps against it, dots are recorded on the moving cylinder surface. The rate of rotation of the cylinder depends on the time axis which is desired. The input data from motors 21 and 22 provide amplitude information to be recorded on the cylinder, whereas the time axis against which this information is plotted, in a rectangular coordinate system, is determined by the speed of the cylinder rotation.

In order to distinguish between the two sets of data which are simultaneously recorded, filament 36 may be impregnated with a different color from 37, so that one recording may be, say, in green and the other in, say, red. Any number of different colors may be used depending upon the number of carriages.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. In a recording instrument having moving record receiving means, the combination comprising fixed means for holding one end of all of a plurality of impregnated filaments, a plurality of impregnated filaments having one end slidably engaging said fixed means, and data actuated means connected to the other end of each of said filaments for moving each of the said other ends of the said filaments transverse to the direction of movement of said record receiving means and substantially parallel to the face of said record receiving means, said means for moving said filaments being off-set from one another to allow the said filaments to pass one another.

2. In a recording instrument having moving record receiving means, the combination comprising a plurality of impregnated filaments, fixed means for slidably engaging one end of the operative portion of all of said plurality of impregnated filaments, a plurality of data actuated means respectively connected to the other operative ends of each of said filaments for moving said filaments transverse to the direction of movement of said record receiving means and substantially parallel to the face of said record receiving means, said plurality of means for moving said filaments being off-set from one another to allow said filaments to pass one another, a plurality of filament storage devices free to permit withdrawal of filament therefrom and having pressure type retarding devices mounted thereupon for restricting the withdrawal of filament therefrom, each of said storage devices being respectively mounted on said means for moving said plurality of filaments, a plurality of actuating means respectively connected to said filament storage devices for drawing said filaments through said fixed means, and means connected to said filaments for imparting tension to the operative portions thereof.

3. A data recorder for simultaneously plotting a time graph for each of a plurality of received signals comprising a record surface arranged to move linearly with time, a plurality of actuating elements one for each received signal, arranged to move in lines parallel to said surface and transverse to the motion thereof, each in accordance with the amplitude of a signal, each of said lines of motion being differently spaced from said surface, a corresponding plurality of stringlike printing elements all having one end slidably engaged at a center point and the other end connected to a one of said actuating elements, and means comprising a printer bar for simultaneously and recurrently striking all of said printing elements against said surface in a line transverse to said motion of said surface periodically to record an element of said graph.

4. A recording instrument as described in claim 3, in which said stringlike printing elements are impregnated with various colors so that the recording for each of said elements is in a different color.
